UNITED STATES PATENT OFFICE

ALLEN SMITH, OF MILLBURY, MASSACHUSETTS, ASSIGNOR TO WHITIN MACHINE WORKS, OF WHITINSVILLE, MASSACHUSETTS, A CORPORATION OF MASSACHUSETTS

BUNCH BUILDING MECHANISM FOR SPINNING FRAMES

Application filed July 16, 1930. Serial No. 468,341.

This invention relates to spinning frames and particularly to frames for winding weft bobbins for automatic looms. For such purposes, the bobbins are preferably provided with a few preliminary turns of weft or filling before the regular traverse of the weft on the bobbins begins.

It is the general object of my invention to provide a relatively simple mechanism for winding such a preliminary bunch of weft or filling and for automatically shifting to the regular filling wind after a bunch of the desired size is produced.

A further object is to provide a construction by which a relatively slow traverse motion is provided during the winding of the bunch and a much more rapid traverse during the regular filling wind.

My present invention relates particularly to improvements in the type of bunch building apparatus described in my prior application, Serial No. 434,427, filed by me March 8, 1930.

My invention further relates to arrangements and combinations of parts which will be hereinafter described and more particularly pointed out in the appended claims.

A preferred form of the invention is shown in the drawings, in which

Fig. 1 is a front elevation of parts of a spinning frame embodying my improvements;

Fig. 2 is a partial end elevation thereof, looking in the direction of the arrow 2 in Fig. 1;

Fig. 3 is a partial front elevation showing certain of the parts in Fig. 1 in a different position;

Figs. 4 and 5 are detail sectional plan views, taken along the line 4—4 and 5—5 in Fig. 3 respectively;

Fig. 6 is a detail sectional end elevation, taken along the line 6—6 in Fig. 4; and

Fig. 7 is a partial side elevation of a bobbin with a bunch wound thereon.

Referring to the drawings, I have shown parts of a spinning frame of the cap type and comprising a frame 10, a creel 11 (Fig. 2) on which spools S of roving are supported, and a plurality of bobbins B sup-

ported on a bobbin rail 12. Upright rods 13 are mounted in fixed position on a cap rail 14 and extend up through the bobbins B, with caps 15 affixed to their upper ends. The bobbins B are rotated by bands 16 from a driving drum 17 (Fig. 2) and the bobbin rail 12 is mounted on lifter rods 18 which are vertically reciprocated by mechanism to be described.

The yarn Y is drawn around the lower edges of the caps 15 and is wound on the rotating bobbins, the yarn traverse being determined by the vertical reciprocation of the bobbins relative to the fixed caps 15. The roving is drawn from the spools S by upper drawing rolls 20, intermediate drawing rolls 21 and delivery rolls 22. Suitable pressure rollers 23, 24 and 25 hold the yarn in contact with the several drawing rolls 20, 21 and 22.

Builder mechanism

The machine is provided with a usual type of builder mechanism, which comprises a chain 30 secured at one end to the lower end of a lifter rod 18 and at the other end to a casting 31 to which a horizontally extending rod 32 is attached. The casting 31 is mounted on or forms a part of a sliding block 33, adapted to move parallel to the drum 17 along guideways 34.

One end of a builder screw 35 is rotatably mounted in a bearing 36 projecting up from the sliding block 33, and a nut 37 is mounted on the screw 35 and is also pivotally connected at 38 with a bracket 39 secured on the side of a builder lever 40. The lever 40 is mounted on a fixed stud 41 and supports a bracket 42 having a roll 43 mounted thereon. The roll 43 engages one face or edge of an intermediate lever 44, swinging about a fixed pivot 45 and supporting a cam roll 46 engaged by the builder cam 47.

The cam 47 is mounted on a horizontal shaft 48 extending transversely of the spinning frame and provided with a worm wheel 49 engaged by a worm 50 rotatable with a short shaft 51. A gear 52 is mounted on the shaft 51 and is engaged by a pinion 53 (Fig. 2) rotatable with a fast pulley 54. A loose pulley 55 and tight pulley 56 are mounted on

the shaft 57 which supports the cylinder 17 and the pulleys 55 and 56 are connected to the tight pulley 54 by a belt 58.

I thus provide for normal rotation of the builder cam 47 in a predetermined speed relation to the rotation of the driving drum 17 and drawing rolls 20, 21 and 22.

The shaft 48 previously described is also provided with a worm 60 (Fig. 2) engaging a worm gear 62 (Fig. 1) mounted on one end of a short shaft 63. A pinion 64 on the other end of the shaft 63 engages an intermediate or idle gear 65 (Fig. 2), which in turn engages a gear 66 mounted to rotate with the builder screw 35.

The gear 66 is preferably mounted on a sleeve 67 slidable but non-rotatable upon the shaft portion 68 of the builder screw 35. The sleeve 67 is provided with a hand wheel 70 by which it may be manually rotated if desired and the sleeve 67 is also provided with an annular groove 71 to receive a latch 72. When it is desired to adjust the builder screw 35 manually, the latch 72 is raised and the sleeve 67 is moved endwise to disengage the gear 66 from the intermediate gear 65.

By the connections above described, the builder screw 35 is normally rotated at slow speed and in definite speed relation to the revolutions of the builder cam 47. Rotation of the builder screw varies the distance between the sliding block 33 and the builder lever 40 and thus permits the block 33 to move toward the right in Fig. 1, thus lowering the bobbin rail 12 and causing the yarn traverse to be shifted progressively upward toward the tips of the bobbins.

Slow speed traverse motion

40 In my present application I provide additional driving connections between the cylinder shaft 57 and the shaft 51 through which the builder cam is rotated.

The gear 53 and pulley 54 previously described are secured to a sleeve 75 (Fig. 4) loosely rotatable on a stud 76 and held thereon by a collar 77. The stud 76 is clamped in fixed position in the frame.

A large pulley 78 is loosely mounted on the sleeve 75 and is provided with a hub portion 79 recessed to receive the driving member 80 of a ball clutch, the member 80 being fixed to the sleeve 75. A plurality of rolls or balls 81 are mounted in recesses 82 in the member 80 and are pressed outward to engage the inner face of the hub 79 by springs 83. When the hub 79 is rotated in a clockwise direction, as viewed in Fig. 6, the rolls or balls 81 will act to clutch the hub to the inner member 80 and thus rotate the sleeve 75, pulley 54 and pinion 53.

The pulley 78 is driven by a belt 85 from a small pulley 86 (Fig. 5) fixed to the end of the cylinder shaft 57.

65 With this construction, it will be apparent

that the large pulley 78 will be continuously rotated at relatively slow speed by the belt 85 and small driving pulley 86 on the cylinder shaft. If the belt 58 is on the loose pulley 55 (as shown in Fig. 1), the driving pinion 53 will be rotated very slowly by the large pulley 78 through the ball clutch above described. If, however, the belt 58 is on the tight pulley 56 (as shown in Fig. 3), the pulley 54 will be rotated at higher speed than the large pulley 78 and the clutch member 80 will be correspondingly increased.

Briefly summarized, the operation is that the builder cam will be driven at normal speed whenever the belt 58 is on the tight pulley 56 but will be driven at much slower speed by the pulley 78 whenever the belt 58 is on the loose pulley 55.

Control mechanism

I will now describe the mechanism by which the belt 58 is shifted from the bunch winding position shown in Fig. 1 to the normal traverse position shown in Fig. 3.

For this purpose, an irregular worm 95 is mounted on one of the upper drawing roll shafts 20 and is continuously rotated therewith.

A belt shifting fork 96 (Figs. 2 and 3) is slidable on a fixed stud 97 and has a rearwardly projecting portion 98 loosely held by a forked member 99 mounted at the lower end of a shipper lever 102. The lever 102 is pivoted at 103 and has an upper end portion 104 extending adjacent the worm 95. The portion 104 is hinged at 105 to the lever 102 and is free to swing toward the axis of the drawing roll shaft 20. A stop screw 106 (Fig. 2) is provided for limiting the swinging movement of the member 104.

A collar 107 is mounted on the member 104 and is provided with a stud 108 normally seated in the spiral groove of the worm 95. A stop 109 limits the swinging movement of the shipper lever to the left in Fig. 1, and a disc 110 on the end of the drawing roll shaft 20 limits swinging movement of the lever in the opposite direction.

The method of operation of the belt shifting mechanism is as follows:

When the spinning frame is to be doffed, the frame is stopped with the roll 46 on the point of the cam 47. The latch 72 is then raised, the gear 66 is disengaged and the builder screw 35 is rotated to raise the bobbin rail 12 to its extreme upper limit of travel. At the same time, the member 104 forming the upper portion of the shipper lever 102 is lifted out of contact with the worm 75 and is swung to the left against the stop 109 as shown in Fig. 1. The gear 66 is then returned to operative position and the spinning frame is started up, but with the belt 58 on the loose pulley 55.

As previously described, the builder cam

will be rotated at very slow speed under these conditions by the belt 85 and large pulley 78.

As the worm 95 rotates with the drawing roll shaft 20, the member 104 is gradually swung to the right in Fig. 1 and the forked member 99 at the bottom of the shipper lever 102 is swung to the left. The slotted opening in the member 99 is substantially 10 wider than the diameter of the stud 98 on the shipper fork and consequently the initial swinging movement of the shipper lever merely takes up the lost motion in the slotted connection between the member 99 and the 15 stud 98.

After the worm 95 has made a predetermined number of revolutions, the stud 108 enters an abruptly sloped portion 112 of the worm 95 and is thrown quickly to the right, 20 shifting the belt 58 to the tight pulley 56. The collar 107 on the shipper lever portion 104 then drops into the annular space between the end of the worm 95 and the disc 110, where it is retained during the continued 25 operation of the spinning frame.

As soon as the belt 58 is shifted to the tight pulley 56, the builder cam will be thereafter rotated at normal speed and the yarn will be traversed much more rapidly on the bobbins.

30 The worm 95 is so designed that the drawing roll shaft 20 will make the desired number of revolutions before the builder motion is rendered operative. The initial position of the lever portion 104 may be varied by adjusting the stop 109.

The slow initial traverse of the yarn during the bunch building operation produces a somewhat elongated bunch, as indicated at B in Fig. 7, and it is found that a bunch thus 40 wound is much less liable to catch and break the filling than a bunch which is deposited entirely at one point on the bobbin, as with my previous construction.

I have thus provided an exceedingly simple and reliable attachment for an ordinary builder motion by which the motion is made to operate very slowly for a predetermined operation of the spinning mechanism, after which the builder motion operates in the usual manner. No change whatever is necessary 50 in the construction of the builder motion itself, in which respect my bunch building attachment is superior to many prior devices for this purpose.

55 Having thus described my invention and the advantages thereof, I do not wish to be limited to the details herein disclosed, otherwise than as set forth in the claims, but what I claim is:—

60 1. In a spinning frame, builder mechanism including a builder cam, actuating means therefor including a driving shaft, means to rotate said shaft at relatively low speed, means to rotate said shaft at relatively high speed, a belt shiftable to effect high speed or

low speed actuation, and automatic means to render the high speed drive operative after a predetermined period of operation of the low speed drive, said automatic means including a belt shifting member, a lever having a lost motion connection to said member, and a worm engaging said lever and having successive threaded portions of fine pitch and coarse pitch respectively, said lever being moved by said fine pitch threads to take up lost motion during a predetermined number of revolutions of said worm and being thereafter moved abruptly by said coarse pitch threads to actuate said shifting member and thereby render said high speed drive effective. 70 75 80

2. The combination in a spinning frame as set forth in claim 1 in which the lever has a worm engaging portion which is manually movable into and out of engaging position with respect to said worm. 85

In testimony whereof I have hereunto affixed my signature.

ALLEN SMITH.
